[57] CLAIM

The ornamental design for a portable inflatable sofa, as
shown and described.

DESCRIPTION

FIG. 1 is a perspective view, taken from the front and left
side, of a portable inflatable sofa showing my new design;
FIG. 2 is a front elevation view thereof;
FIG. 3 is a left side elevation view thereof. The right side
elevation view is a mirror image of the view shown in FIG.
3.
FIG. 4 is a top plan view thereof;
FIG. 5 is a rear elevational view thereof; and,
FIG. 6 is a bottom plan view thereof.
